UNITED STATES PATENT OFFICE.

GEORGE F. ROYER, OF WILKES-BARRE, PENNSYLVANIA, ASSIGNOR TO ROYER FOUNDRY & MACHINE CO., OF WILKES-BARRE, PENNSYLVANIA, A CORPORATION OF PENNSYLVANIA.

SEPARATOR FOR GRANULAR MATERIAL.

Application filed February 14, 1924. Serial No. 692,789.

To all whom it may concern:

Be it known that I, GEORGE F. ROYER, a citizen of the United States, residing at Wilkes-Barre, in the county of Luzerne and 5 State of Pennsylvania, have invented new and useful Improvements in Separators for Granular Material, of which the following is a specification.

The present invention relates to improvements in separators for granular material of the type illustrated in my copending application Serial No. 573,408.

The particular object of the present invention is to provide a separating belt which 15 will be an improvement upon the belt constituting one element of the apparatus of said earlier application.

In the apparatus illustrated in the application referred to the separating belt consists of a body of suitable fabric from 20 which project sprigs or pins providing on the outer surface of the belt a series of pockets to receive particles of sand, loosened from a mass supported on the belt. With 25 the earlier construction the several pins were each independently secured to the belt body and, therefore, it was difficult to maintain them in the desired relation to the belt. It will be understood that the pins or sprigs 30 should each form a right angle with the body of the belt and the strains or stresses placed upon the points or free ends thereof had a tendency to enlarge the passages in the belt within which the pins were fixed 35 so that after a short time the desired right angle relation between the pins and belt was destroyed.

The object of the present invention is to 40 provide a separator belt with sprigs of such form that they will maintain the desired relation to the belt and by which the maximum amount of flexibility of the teeth will be provided without impairing or affecting the connection between the several teeth 45 and the body of the belt.

In the accompanying drawing—

Fig. 1 is an elevation of a separator for 50 granular material including a belt constructed in accordance with the present invention.

Fig. 2 is a transverse sectional view of the apparatus shown in Fig. 1.

Fig. 3 is a section through the improved separator belt, on an enlarged scale, substantially on the line 3—3 of Fig. 5. 55

Fig. 4 is a section on the line 4—4 of Fig. 3.

Fig. 5 is a plan of the parts shown in Figs. 3 and 4.

Fig. 6 is a view similar to Fig. 4 illustrating a slight modification.

Referring to the drawing, the apparatus illustrated, which is of the form shown in the earlier application Serial No. 573,408, above referred to, comprises a supporting frame having a base or foot casting 1, a head casting 2, an endless separator belt supported on driving rolls or pulleys 3 and 4, a hopper 5 adapted to laterally confine a mass of material supported on the upper run of the belt; and an electric motor 6 for driving the separator belt at a relatively high speed. 70

In order that the apparatus may be readily movable from place to place, wheels 7 are provided for supporting the head casting 2 and a suitable handle 8 is connected to the base casting 1. 75

The separator belt comprises a body 9 of fabric or other suitable material and the outer face of which is provided with a series of projecting sprigs forming small pockets which receive particles of sand dislodged from a mass supported on the upper run of the belt within the hopper 5, as the belt moves beneath such mass, the collected particles being discharged by centrifugal force as they reach the upper end of the path of travel of the belt about the supporting roll or pulley 3. 80

According to the present invention the several sprigs or separating points are not individually connected to the body of the belt. As shown, a series of such sprigs 10 are formed integral with a base member or flange 11. 85

The series of sprigs and base member 11 may be stamped from a strip of spring metal, which is bent so that the sprigs 10 will extend substantially at right angles to the base member 11, which is secured to the body of the belt. 90

In the embodiment of the invention illustrated a series of apertures are punched or

otherwise formed in each base member 11 and through these and the belt extend staples 12, the free ends of which are suitably clinched against the lower face of the belt so that the sprig plates are firmly and securely attached to the belt.

It will be seen that the spaces separating the teeth or sprigs 10 of each plate do not extend continuously to the surface of the 10 base flange 11, but there is a slight upstanding portion at the rear end of the flange 11.

In order that the several sprigs may have a maximum amount of strength without impairing their flexibility it is preferred to 15 arrange the plates so that a plurality thereof will be secured to the belt by a common row of staples. In the embodiment of the invention illustrated in Figure 4, each set of sprigs is composed of three laminations 20 or superposed spring metal plates, the staples 12 acting to hold the members of each group in close relation and firmly secure them to the body of the belt.

As shown, the finger portions of the several laminations are preferably made of different lengths, being gradually shorter from the front to the rear of each sprig. This is 25 shown particularly in Figure 4.

The number of laminations or members 30 in each sprig may be varied. While very good results have been obtained with a construction in which each sprig is composed of three laminations or members as shown in Figure 4, it is possible that two-leafed sprigs, as shown in Figure 6, could be advantageously used or, if desired, the number 35 of laminations may be further increased.

In operating a separator of the form to 40 which the present invention relates the separator belt is driven at a relatively high speed, say a surface speed of from six hundred (600) to nine hundred (900) feet per minute. The mass of used moulder's sand which may contain undesirably large particles of gravel, nails, pieces of metal and other foreign material is deposited in the 45 hopper 5 and rests upon the upper run of the belt.

As the sprigs travel through and beneath 50 the mass of material the smaller, desired particles of sand are separated and collected in the sockets formed between the sprig plates while the undesirable larger pieces and foreign substances, which cannot be received within the pockets are caused to move downward over the upper ends of the sprigs to the lower end of the hopper 5. As in the 55 apparatus of the earlier application referred to, means are provided for positively preventing such foreign material, supported on the sprigs from traveling over the pulley 3. As the belt passes about this pulley 3, traveling at the high speed mentioned, the 60 smaller particles of sand which have been

collected in the pockets are discharged by 65 the action of centrifugal force in a stream through the air which permits the escape of any gases that may have been retained within the mixture and thoroughly aerates the separated particles.

By making the sprigs of the laminated form described and illustrated the desired strength of such parts is provided without interfering with the necessary flexibility 70 thereof.

By making the sprigs of laminated form 75 they are adapted to yield when striking a heavy piece of metal, for example, without liability of breaking or of loosening the connection by which they are secured to the body of the belt.

It will be understood that the drawing is intended to be merely illustrative of the invention, and that there can be considerable variation as regards the proportions of the several parts without departing from the 80 invention.

Preferably the sprig plates will be of such 85 length that each will extend throughout the width of the operative portion of the belt.

Having thus described the invention what 90 is claimed is:

1. A separator comprising a driven endless belt provided with outwardly projecting sheet metal sprigs arranged in rows extending transversely of the belt, the sprigs being arranged in groups and all the members of each group formed integral with a base flange that overlies and is attached to the belt, and means for laterally confining a body of material to be treated in the path of travel of the free ends of the sprigs.

2. A separator comprising a driven endless belt provided with outwardly projecting sprigs arranged in rows extending transversely of the belt, said sprigs being arranged in groups all the members of each group being integral with a flange, common to all the members of the group that overlies and is attached to the belt, and means for laterally confining a body of material to be treated in the path of travel of the free ends of the sprigs.

3. A separator comprising a driven endless belt, a series of plates each shaped to provide a base member extending parallel to the outer face of the belt and an outwardly projecting member formed into a series of tongues or sprigs, means fastening the base members of said plates to the belt, and means for laterally confining a body of material to be treated in the path of travel of the free ends of the sprigs.

4. A separator comprising a driven endless belt, a series of plates each shaped to provide an apertured base member extending parallel to the outer face of the belt and an outwardly projecting member formed

into a series of tongues or sprigs, means extending through the apertures in the base members and securing the plates to the belt, and means for laterally confining a body of material to be treated in the path of travel of the free ends of the sprigs.

5 5. A separator comprising a driven endless belt, a series of laminated sprigs attached to the belt and extending outward therefrom, and means for laterally confining a body of material to be treated in the path of travel of the free ends of the sprigs.

10 6. A separator comprising a driven endless belt, a series of laminated sprigs attached to and extending outward from the belt, the individual laminations of each sprig being of different lengths, and means for laterally confining a body of material to be treated in the path of travel of the free 20 ends of the sprigs.

15 7. A separator comprising a driven endless belt, a series of laminated sprigs attached to and extending outward from the belt, the individual laminations of each sprig 25 being of decreasing lengths from front to rear of the sprig in the direction of travel of the belt, and means for laterally confining a body of material to be treated in the path of travel of the free ends of the sprigs.

20 8. A separator belt comprising a suitable body and a series of plates secured to the outer face of the belt and each provided

with a plurality of integral outwardly projecting sprigs.

9. A separator belt comprising a suitable 35 body and a series of plates secured to the outer face of the belt and extending transversely thereof, each plate being provided with a series of integral outwardly projecting sprigs.

40 10. A separator belt comprising a suitable body and a series of spring metal plates secured to the body and each having a plurality of outwardly projecting integral sprigs.

45 11. A separator belt comprising a suitable body and a series of sheet metal plates, each plate being bent upon itself to form a base member, that is secured to the belt, and a member that extends outward from the base 50 and is slotted to provide a plurality of sprigs.

55 12. A separator belt comprising a suitable body and a series of sheet metal plates, each plate having a plurality of sprigs or spaced fingers along one edge and being bent upon itself to form a base, integral with and extending substantially at right angles to the length of the sprigs, that is secured to the body of the belt.

60 In testimony whereof I have hereunto set my hand.

GEORGE F. ROYER.
